James N. Thomas

Attorney

UNITED STATES PATENT OFFICE.

JAMES N. THOMAS, OF GARBERVILLE, CALIFORNIA.

MACHINE FOR SPLITTING SHAKES.

Application filed March 4, 1924. Serial No. 696,816.

To all whom it may concern:

Be it known that I, JAMES N. THOMAS, a citizen of the United States, and a resident of Garberville, county of Humboldt, and 5 State of California, have invented a new and useful Machine for Splitting Shakes, of which the following is a specification.

The present invention relates to improvements in machines for splitting shakes from 10 previously prepared blocks of wood commonly known as bolts. These blocks are usually made of a length substantially corresponding to the length of the shakes to be manufactured, of a width about six inches, 15 which corresponds to the width of the shakes, and of a thickness sufficient to allow a large number of shakes to be cut out of the same. It is proposed in the present invention to provide a convenient way of 20 separating thin slices of a desired thickness from a bolt and to utilize for this purpose a knife blade moving horizontally. This manner of arranging the knife blade allows two different bolts disposed on opposite sides 25 of the blade to be worked on alternately by successive reciprocations of the blade.

It is also proposed in the present invention to provide suitable means for clamping two bolts in such a manner that the thickness 30 of the shake to be separated can be exactly determined. It is furthermore proposed to arrange the clamping device in such a manner that after an individual shake has been sliced from the bolt the former is automatically freed from the clamp 35 and pushed out of the way. Further objects and advantages of my device will appear as the specification proceeds.

The preferred form of my invention is 40 illustrated in the accompanying drawing in which Figure 1 is a plan view of my machine; Figure 2 a side elevation of the same; Figure 3 an enlarged detail view taken along line 3-3 of Figure 1; Figure 45 4 an enlarged detail view taken along line 4-4 of Figure 1; Figure 5 an enlarged detail view in plan of a mechanism for positioning the outer end of the bolt; and Figure 6 an enlarged side elevation of the said 50 mechanism. While I have shown only the

preferred form of my invention, I wish to have it understood that various changes or modifications may be made within the scope of the claims hereto attached without departing from the spirit of the invention. 55

My machine is supported on two tables (1) and (2) disposed in parallel relation so as to leave a small crack (3) between the same. The table (1) has supported thereon near its extreme end two blocks (4) and in 60 the central portion thereof two spaced blocks (6), all the four blocks being substantially symmetrical in form and running parallel to one another and being disposed transversely to the length of the table with 65 the edges substantially flush with the edges of the table.

The table (2), which will be referred to as the delivery table as contra-distinguished from table (1) which is the receiving table, 70 is provided with four blocks (7) in places corresponding to the blocks on the receiving table, so that a guide rail (8) being disposed centrally over the crack (3) between the two tables may be supported on 75 the blocks and clamped to the same by means of the clamps (9). This guide rail is formed to receive thereon, with freedom of sliding motion, the back (11) of the blade (12) which latter thus depends vertically 80 from the rail and may be reciprocated on the rail by any suitable means, as by the rack and pinion arrangement (15) shown in the drawing.

Each of the blocks (4) on the receiving 85 table forms a pair with the nearest one of the blocks (6), which pair serves as a guide for a bolt of wood, and the blade is made of such a length that when pushed over to the right it clears the space controlled by 90 the left pair of blocks, and if pushed to the left it clears the space controlled by the right pair of blocks.

Between each pair of blocks (4) and (6) 95 there are provided on the receiving table two skids (13) on which the bolt (14) may be placed and pushed forward into an operative position by the operator. The bolts as commonly manufactured vary somewhat in length, and to allow bolts of various 100

lengths to be clamped between the two blocks (4) and (6) I provide a spring (16) engaging one end of the bolt as the latter is advanced by the operator.

5 For the positioning of the bolt prior to the cutting action, it is necessary to provide means allowing the thickness of the slice to be separated to be readily adjusted, and to also provide means allowing of the individual adjustment of the positioning means at either end of the block. To fulfill these requirement I provide individually adjustable positioning means or stopping means for the advancing bolt at either end of the 10 same. Remembering that the blade reciprocates in the space between the two tables, I allow the bolt to be advanced over the crack between the tables until it strikes the two stopping elements (17) and (17'), the 15 former engaging the inner end of the bolt and the latter the outer end.

The stopping element (17) consists of a T shaped plate (18) guided transversely to the receiving table in the guide (19) 20 secured to the block (7) with a spring (21) bearing against the end of the plate (18) and a stationary plate (22) offering yielding resistance to the advancing bolt (14) attempting to push the plate (18) backward. In addition to this yielding resistance to the advancing bolt (14), I provide a 25 positive stop in the form of the pin (23) engaging with the end of the T plate as the latter is pushed backwardly by the advancing bolt. The pin (23) may be inserted in any one of the plurality of holes (24) whereby its exact position may be accurately adjusted so that the advance of the inner end of the bolt may be definitely 30 stopped at any point desired.

The outer end of the advancing bolt is taken care of by the stopping member (17') which latter comprises a block (26) pivoted as shown at (27) to a slide (28) adapted 45 to move longitudinally of the receiving table in a guideway (29). The inner end (31) of the block is normally urged forward in front of the advancing bolt (14) by means of the spring (32) which latter, however, yields to the advancing bolt until the block (31) comes to a definite stop when striking the stationary stud (33), the position of which latter may be adjusted by utilizing any one of the plurality of holes (34).

55 This arrangement thus far described allows the bolt to be manually pushed forward on the skids (13), the spring (16) eliminating side play between the blocks (4) and (6), and the positioning or stopping elements on the receiving table engaging the opposite ends of the advancing bolt, first offering yielding resistance and finally stopping the bolt at the exact point desired so that a clearly defined portion of 60 the bolt projects beyond the crack between

the two tables and is ready to be sliced or separated from the bolt when the blade is thrust forward.

The back (11) of the blade is provided at either end with an extension (36) which just before the completion of the slicing operation strikes the upper end of the lever (37) pivoted to the table as at (38) and engaging by means of the pin (39) the block (26). It will be remembered that the latter block is supported on the slide (28) and the engagement of the extension (36) with the lever (37) has the effect that the block (26) and the slide (28) are pushed sideways over the resistance of a spring (41) whereby the extreme point of the block (26) is made to clear the outer end of the bolt (14). The lever (37) is dimensioned so that after being pushed into a slanting position, shown in Figure 2, by the extension (36), it allows the extension (36) to ride over the same and to thereby hold it in the said slanting position.

While the outer end of the bolt or rather of the shake or slice separated therefrom is thus freed from the stopping element (17'), the inner end of the shake is still confined between the blade and the block (18), but is pushed sideways by the member (43) striking the inner or near end of the shake. When the shake is thus pushed sideways its outer or far end, which has been previously cleared of the engagement with the stopping member (17'), rides along the face of the same, which is made slanting and curved in the manner shown in Figure (1) so as to push the far end of the shake away from the bolt.

The member (43) comprises a strip of metal slidably supported between the two blocks (6) in brackets (44) with two springs (46) tending to hold the strip in a midway position. The strip is formed with its ends off-set so that the latter may lie flat against the blade and are sufficiently thin that they may be pushed into the space left between the blade and the stopping member (17) when the bolt is positioned.

The back of the blade is provided with a stud (47) which engages with the strip (43) as shown at (48) at the time the blade has just completed its cutting action, so that as soon as the shake is separated from the bolt, the extreme end of the strip of metal (43) is pushed against the inner or near end of the shake for freeing the latter from the member (18) and allowing the same to drop on the receiving table. When the blade is moved in the opposite direction for cutting a slice of the bolt on the left hand side of the machine, a lug (49) engages with the strip (43) for pushing the same in the opposite direction for performing the same function of freeing the shake cut on the other side.

The operation of my machine is as follows: Two bolts (14) are placed on the skids (13) and are manually advanced. Assuming that the cutting blade is on the left hand side of the machine as viewed in Figure 1, the right hand bolt is advanced until its front edge passes the crack between the tables and comes in contact with the two stopping elements (17) and (17') which later at first yieldingly and finally definitely stop the advance. The blade is now made to move to the right and cuts off a slice corresponding to the shape of the shake.

Just before completing the cutting operation the extension (36) strikes the lever (37) and pushes the block (26) to the right over the resistance of the spring (41). Immediately upon completing the cutting operation the lug (47) engages with the sliding strip (43) and forces its extreme end into the space left between the blade and the block (18) whereby the shake is forced outwardly toward the right. The far end of the shake slides along the curved inner face of the block (26) and is thereby pushed away from the bolt and allowed to drop on the receiving table. The same operation is now repeated on the left hand side with the lug (49) pushing the sliding strip (43) in the opposite direction and with the spring (41) returning the stopping member (17') to its original position as soon as the extension (36) of the back of the blade becomes disengaged from the lever (37).

35 I claim:

1. In a bolt splitting machine of the character described, two elongated tables placed alongside of one another so as to form a crack, a blade mounted for reciprocal motion in and over said crack and means for securing a bolt on the tables in operative relation to the blade so as to slightly project from one of the tables over the crack comprising transverse guide means for the bolt on one of the tables and stopping elements engaging opposite ends of the bolt mounted on the other table, one of the elements including a retractile sliding block and adjustable means for effecting a positive stop of the block and the other element including a pivoted block, yielding means opposing pivotal motion and adjustable means for positively stopping pivotal motion at a predetermined point.

55 2. In a bolt splitting machine of the character described, two elongated tables placed alongside of one another so as to form a crack, a blade mounted for reciprocal motion in and over said crack and means for securing a bolt on the tables in operative relation to the blade so as to slightly project from one of the tables over the crack comprising transverse guide means for the bolt on one of the tables and stopping elements 60 engaging opposite ends of the bolt mounted

on the other table, one of the elements including a retractile sliding block and adjustable means for effecting a positive stop of the block and the other element including a pivoted block, yielding means opposing pivotal motion and adjustable means for positively stopping pivotal motion at a predetermined point in combination with means for laterally retracting the latter block for clearing the bolt at the end of the splitting operation.

3. In a bolt splitting machine of the character described, two elongated tables placed alongside of one another so as to form a crack, a blade mounted for reciprocal motion in and over said crack and means for securing a bolt on the tables in operative relation to the blade, so as to slightly project from one of the tables over the crack comprising transverse guide means for the bolt on one of the tables and stopping elements engaging opposite ends of the bolt mounted on the other table, one of the elements including a retractile sliding block and adjustable means for effecting a positive stop of the block and the other element including a pivoted block, yielding means opposing pivotal motion and adjustable means for positively stopping pivotal motion at a predetermined point in combination with means for laterally retracting the latter block for clearing the bolt at the end of the splitting operation and with means for imparting endwise motion to the separated portion thereafter whereby the same is freed from the first element.

4. In a bolt splitting machine of the character described, guide means allowing a bolt to be advanced therebetween, stops for the front edge of the bolt and a blade mounted for reciprocating motion for separating a slice from the bolt, one of the stops having means for laterally retracting the same at the end of the cutting operation associated therewith so as to free the separated slice from the same, and means being provided for imparting endwise motion to the separated piece for clearing the same from the other stop.

5. In a bolt splitting machine of the character described, guide means allowing a bolt to be advanced therebetween, stops for the front edge of the bolt and a blade mounted for reciprocating motion for separating a slice from the bolt, one of the stops including a pivoted block, yielding means opposing pivotal motion and adjustable means for positively stopping pivotal motion at a predetermined point in combination with means for laterally retracting the latter block for freeing the separated piece from the said stop.

6. In a bolt splitting machine of the character described, guide means allowing a bolt to be advanced therebetween, stops for the

front edge of the bolt, and a blade mounted for reciprocating motion for separating a slice from the bolt, one of the stops including a pivoted block, yielding means opposing pivotal motion and adjustable means for positively stopping pivotal motion at a predetermined point in combination with means for laterally retracting the latter block for freeing the separated piece from the said stop, and with means for imparting 10 endwise motion to the separated piece whereby the same is freed from the other stop.

JAMES N. THOMAS.
